UNITED STATES PATENT OFFICE

2,616,279

FLEXIBLE DIAPHRAGM TYPE OF LAUNDRY APPARATUS

Thomas S. Watson, Milwaukee, Wis.

Application August 23, 1948, Serial No. 45,679

6 Claims. (Cl. 68—21)

1

The invention relates to laundry apparatus. The general object of the invention is to provide a laundry apparatus, more particularly for home use, in which washing, rinsing, and extracting or drying operations are carried out while the clothes are in a receptacle including a flexible bag.

A further object of the invention is to provide an apparatus in which the washing operation is effected by circulating wash water through the clothes.

A further object of the invention is to provide an apparatus in which the washing operation is effected by circulating wash water through the clothes, the rinsing operation by circulating rinse water through the clothes through parts of the wash water circulating system, and the extracting or drying operation is effected by water under pressure acting on the flexible bag containing the clothes.

A further object of the invention is to provide means for vibrating the clothes during the washing and/or rinsing operation.

The invention further consists in the several features hereinafter set forth and more particularly defined by claims at the conclusion hereof.

In the drawings:

Fig. 1 is a front elevation view of an apparatus embodying the invention, parts being broken away and parts being shown in section;

Fig. 2 is a detailed side elevation view of the apparatus, parts being broken away and parts being shown in section;

Fig. 3 is a top plan view of the apparatus with the cover shown in dotted lines in its open position;

Fig. 4 is a detailed vertical sectional view taken on the line 4—4 of Fig. 1;

Fig. 5 is a detailed vertical sectional view taken on the line 5—5 of Fig. 2;

Fig. 6 is a detailed horizontal sectional view taken on the line 6—6 of Fig. 5;

Fig. 7 is a diagrammatic view showing the hydraulic system;

Fig. 8 is a detailed vertical sectional view taken on the line 8—8 of Fig. 3.

Referring to the drawings, the numeral 10 designates a metal tube or support which is provided with a partition 11 to form a tank or wash fluid storage space 12. The top of the tube 10 is provided with a reinforcing metal ring 13 suitably welded thereto and is closed off by a container comprising a metal top ring 14 welded to the ring 13 and also to a sheet metal container body 15. The container body is cylindrical with

2

a conically curved bottom having a central opening 16 connected by a pipe 17 with a source of hydraulic fluid.

A bag 18 of a rubber composition or other suitable flexible material fits within the container and its reinforced rim 19 is adapted to fit in a groove 20 in the rim or ring 14 and a mating groove 21 formed in a metal clamping ring 22 secured to the rim 14 by a plurality of screws 23. A deflector lining member 24 of bag-like form and of suitable flexible material extends down into the bag 18 and is provided with a central opening 25 in its bottom. The top portion of the member 24 is secured to the top of ring 22 by a recessed metal clamping ring 26 which is secured to the ring 22 by screws 27. The ring 22 is provided with an inwardly flaring passage 28 which connects by a conduit fitting 29, extending through the wall of the tube 10, with a pipe 29a.

A metal cover 30 fits over the top of the container and is hingedly connected with the support 10, so that it may be swung to one side of the container as shown in dotted lines in Fig. 3. The cover includes a base ring 32, a cover top 33, and an apertured cover member 34 integrally secured together. The base ring has a laterally extending lug 35 secured to a hinge cap 36 in which a hinge pin 37 carried by a bracket 38 secured to the support 10 is mounted.

For securing the cover in closed position two oppositely disposed semi-cylindrical flanged members 39 and 40 are provided. The member 39 is secured to the cover and has a flange 41 adapted to engage the underside of a laterally projecting portion 42 of the ring 14. The member 40 is secured to the ring 14 and has a flange 43 adapted to engage the upperside of a laterally projecting portion of the cover ring 32. Thus when the cover is moved to closed position, the flanges 41 and 43 lock or hold the cover against longitudinal movement relative to the container, but being half rings, they do not interfere with the swinging of the cover to one side of the container when desired, the rings 39 and 40 being recessed as shown in Fig. 2 at one joint to clear the conduit 29.

The cover top 33 has a drain opening 44 connected by a fitting 45 with a three way valve fitting 46 which has a drain outlet connection 47 and a wash water return pipe connection 48 with the tank 12.

Referring now to Fig. 7, the pipe 29a extends down through the tank 12 and is connected to the outlet of a centrifugal or other suitable rotary

motor driven pump 49 whose inlet is connected by a pipe 50 with the bottom of the tank 20. The pipe connection 29a has a check valve fitting 51 therein and a T fitting 52 which connects by piping 53 with a pipe 54 that is provided with suitable four way valves 55 and 56. The valve 55 also connects with a hot water supply pipe 57 and a wash water supply pipe 58 leading into the tank 12. The valve 56 also connects with a cold water supply pipe 59 and a pipe 60 which leads to the inlet of a high pressure rotary motor driven pump 61 whose outlet is connected by a pipe 62 with a three way valve 63 that also connects with the pipe 17 and with a waste pipe connection 64 leading out of the tank 12. The tank 12 has a valve controlled drain outlet 65.

The pipe 60 has a branch pipe connection 66 which connects with the pipe 62 and is provided with a check valve fitting 67, so that water at city pressure may be delivered to the pipe 62 before this pressure is boosted by the operation of the pump 61.

The storage tank 12 may be provided with an access opening 68 closed by a door 69 hinged to the support 10 at 70 and held in closed position by a pivotally mounted latch 71 engageable with a keeper 72. Soap or washing powders may be introduced in the tank 12 through opening 68.

The operation of the apparatus is, as follows: With the cover 30 swung to open position the clothes are placed in the space provided by the bags 18 and 24 and the washing fluid is made up in the tank 12 by introducing water through the pipe 58 at the desired temperature obtained from the supply pipes 57 and 59 by the operation of the valves 55 and 56 and washing powder or soap through the opening 68. The cover is closed, and the pump 49 is then started, and it draws the washing fluid from the tank 12 through the pipe 50 and forces it upwardly through the pipe 29a, fitting 29, and passage 28 into the space between the deflector 24 and the bag 18 from whence it flows through the opening 25 upwardly through the clothes and out through the perforations 73 in the cover member 34 into the space 74 in the cover, thence through the fitting 45, valve 46, and pipe 48 back to the tank 12. The washing fluid is thus continuously circulated through the clothes to cleanse the dirt therefrom for a sufficient length of time to accomplish this purpose. The pump 49 is then stopped, the valve 46 turned to connect pipe 47 with fitting 45, and either or both of the valves 55 and 56 operated to admit fresh water at the desired temperature into the pipe 53 from which it passes into the pipe 29a, thence through fitting 29 and passage 28 into the space between the deflector 24 and the bag 18 from whence it flows through the opening 25 upwardly through the clothes and out through the cover as first described and then through the fitting 45, valve 46, and pipe 47 to waste, this water acting to rinse the clothes, it being noted that the check valve 51 prevents rinse water passing into the pump 49. The rinsing operation is continued until the clothes are thoroughly rinsed, and then the valve 55 is closed, if open, and the valve 63 moved to connect pipes 62 and 17 in circuit flow relation and the valve 56, being open or opened, water at city pressure is introduced into the pipes 60 and 66 and past check valve 67 into pipes 62 and 17 and thence into the bottom of the container between the bag 18 and said container and exerting its pressure on the bottom of said bag 18 lifts it with the clothes therein upwardly toward the cover. Shortly

thereafter the pump 61 is started, and it then takes water from the pipe 60 and raises its pressure and forces it through the pipe 62 and 17 into the container, this higher pressure acting to close the check valve 67 and also acting on the bag 18 to force the load of clothes therein up against the apertured member 34 of the cover and squeeze or force the water in the clothes into the space 74 from which it flows through fitting 44 to the drain 47, the valve 46 being then set for this purpose. Thus the water is extracted from the clothes, and after this has been completed, the pump 61 is shut off or stopped, the valve 63 turned to connect the pipe 17 with the waste pipe 64 to release the pressure, whereupon the cover may be swung to open position, and the washed, rinsed, and partly dried clothes removed. By the term "partly dry" I mean as much or more water has been extracted from the clothes than is done by the usual operations of wringing or spin drying. While the deflector member 24 has been shown as having a relatively small central opening 25 in its bottom, this opening may in some instances be considerably larger to suit the size of the container and the fluid pressures used. This deflector has been found to be of considerable importance as it protects the clothes from being torn by the bag 18 which may happen where the bag 18 alone is used since the bag sometimes folds or kinks up at its top and bottom portions and in doing so tears the clothes contained therein.

As shown in Fig. 4, I may mount a vibrator 75 on a centrally disposed shaft 76 connected to the cover 34 for vibrating said cover and container and hence the clothes in the container during the washing and/or rinsing operation. Any suitable vibrator may be used, and I have shown one of the electric type.

I desire it to be understood that this invention is not to be limited to any particular form or arrangement of parts except in so far as such limitations are included in the claims.

What I claim as my invention is:

1. In a laundry apparatus, the combination of a container having a flexible bag extending into it and provided with an outlet, an apertured cover for said outlet, means for introducing fluid under pressure between the container and the bag to collapse the bag and force water from the clothes in the bag through said outlet, an inner lining for the bag spaced from the inner side of said bag to provide a flow space between it and the bag, and a conduit communicating with this flow space.

2. In a laundry apparatus, the combination of a container having an open end and a flexible bag extending from said open end into said container, an apertured cover for said open end, means for introducing fluid under pressure between the container and the bag to collapse the bag and extract water from the clothes in the bag through said outlet, and an inner flexible clothes protective lining disposed within the sides and bottom portions of the bag to prevent tearing of the clothes by the bag during the extraction process.

3. In a laundry apparatus, the combination of a container having a top rim portion, a flexible bag secured to said rim portion and extending into said container, a tank associated with said container, an apertured cover detachably secured to said top rim portion and having a passage leading therefrom connected with said tank, a passage in the rim portion of said container

above the bag, means connected with said last named passage, the said passage in the cover and said tank for circulating a washing fluid through clothes placed in the bag to wash said clothes, means connected with the passage in the cover and said passage in the rim portion of the container to pass rinse water through the clothes, and means for introducing fluid under pressure into the container between said container and the bag to force the bag and the clothes therein toward the apertured cover to extract water from the rinsed clothes.

4. In a laundry apparatus, the combination of a container having a top rim portion, a flexible bag secured to said rim portion and extending into said container, a tank associated with said container, an apertured cover detachably secured to said top rim portion and having a passage leading therefrom connected with said tank, a passage in the rim portion of said container above the bag, means connected with said last named passage, the passage in the cover and said tank for circulating a washing fluid through clothes placed in the bag to wash said clothes, means connected with the passage in the cover and said passage in said rim portion of the container to pass rinse water through the clothes, means for deflecting the washing fluid and the rinse water on its introduction through said passage in said rim portion toward the bottom of the bag, and means for introducing fluid under pressure into the container between said container and the bag to force the bag and the clothes therein toward the cover to extract water from the rinsed clothes.

5. In a laundry apparatus, the combination of a container having a top rim portion, a flexible bag secured to said rim portion and extending into said container, an apertured cover detachably secured to said top rim portion and having a passage leading therefrom, a flexible clothes-protecting deflector extending into said bag and spaced therefrom to direct fluid toward the bottom of said bag, a passage in said rim portion communicating with the space between the deflector and the bag, means connected with said last named passage and the passage in the cover for circulating a washing fluid through the clothes placed in the bag to wash the clothes, means also connected to said passages to pass

rinse water through the clothes, and means for introducing fluid under pressure into the container between said container and the bag to force the bag and the clothes toward the cover to extract rinse water from the clothes.

- 5 6. In a laundry apparatus, the combination of a container having a top rim portion, a flexible bag secured to said rim portion and extending into said container, an apertured cover detachably secured to said top rim portion, a tank below the container for washing fluid, a passage in said rim portion of the container above the bag, a circulating pump for the washing fluid, means connecting the passage in said cover with said tank, and means connecting said pump with said tank and with the passage in said rim portion whereby the washing fluid in said tank is circulated through clothes placed in the bag to wash the clothes, means also connected with the passage in said cover to pass rinse water through the clothes, flexible means disposed within the sides and bottom portions of the bag for deflecting the washing fluid and the rinse water on its introduction into the container toward the bottom of the bag to cause said fluid and rinse water to flow upwardly through the clothes in the bag, and means for introducing fluid under pressure between the container and the bag to force the bag and the clothes therein toward the apertured cover to extract water from the rinsed clothes.
